CHRISTIAN WILHELM PAUL HEYLANDT, OF BERLIN-LANKWITZ, GERMANY

METHOD OF AND DEVICE FOR THE REGASIFICATION OF LIQUEFIED GASES

Application filed February 16, 1928, Serial No. 254,913, and in Germany March 29, 1927.

This invention relates to a process and apparatus for regasifying liquefied gases, the object of the invention being to provide a process and apparatus of this character by means of which the tension resulting from the self-compression of gases which evaporate from the liquid in pressure containers is progressively increased during the gasification, said increased tension being utilized to increase the heating effect and thereby to increase the speed of evaporation of the liquid.

It has been demonstrated by numerous experiments that if liquefied gases are introduced into a pressure vessel for producing pressure gases in said vessel by self compression, the gasification, after the receptacle has been closed, proceeds very slowly, especially at the beginning, owing to the necessity of guarding against too violent gasification. The object, therefore, of the present invention is to reduce to a minimum the delay in obtaining the highest final pressure. This result is obtained by the introduction of gases under a predetermined pressure into the pressure tank thereby artificially increasing the pressure within the gasification chamber in said pressure tank, whereby gasification is accelerated under the influence of the increase in tension and evaporation occurs at such a rate that the liquid in the container is in a very short time converted into gas of the desired pressure.

The drawing accompanying this specification illustrates in partly sectional side elevation an apparatus adapted for carrying out the improved process. In said drawing, 1 designates a pressure tank or container within which is disposed a thin-walled inner receptacle 7 spaced from the wall of pressure tank 1 and which receptacle communicates by means of a pipe 5 with a receptacle 2, an extension 5^a of which pipe may serve as a consumption conduit. The wall of the inner receptacle 7 is provided near the upper end thereof with a plurality of perforations 8 by which the interior of the receptacle is in communication with the space between the walls of the receptacle 7 and pressure tank 1. The cover 9 common to both the receptacle and pressure tank is provided with a filling open-

ing normally closed by a plug 6. The communication between the receptacle 7 and receptacle 2 is controlled by a ball closure 4 and pressure lever 3, so that at a suitable time, soon after the receptacle 7 has been filled and the filling opening closed, gas at a predetermined pressure is permitted to pass from the receptacle 2 into said receptacle 7 and through the openings 8 into the space between the walls of said receptacle and the pressure tank 1 thereby equalizing the pressure within and without the receptacle 7 and augmenting the tension in the pressure tank. If desired, the closure 6 of the vessel 1 may be connected with the lever 3 thereby to admit the auxiliary pressure gas immediately at the commencement of the self-compression. It is to be understood that while I have for purposes of illustration shown only one pressure tank and one auxiliary pressure receptacle, a plurality of pressure tanks may be connected in series with a single auxiliary receptacle or a number of auxiliary receptacles may be connected with a single pressure tank, without departing from the spirit and scope of the present invention.

From the foregoing it will be seen that the layer of gas between the pressure tank and the inner receptacle, which gas at the beginning of the operation forms a very good insulation, is converted by the addition of auxiliary pressure gas into a good heat-conducting layer so that the speed of evaporation is materially increased.

Having thus described my invention, what I claim is:

1. The process of gasifying liquefied gases which consists in filling said gases into a vessel insulated against heat, and treating the insulating medium to cause the same to act as a heat-exchanging medium.

2. The process of gasifying liquefied gases which consists in filling said gases into a vessel insulated against heat by means of a fluid insulating medium, and treating said fluid medium to cause the same to act as a heat-exchanging medium.

3. The process of gasifying liquefied gases which consists in filling said gases into a vessel insulated against heat by means of a fluid

insulating medium and subjecting said fluid medium to the action of a gas under pressure thereby to compress the fluid and cause it to act as a heat-exchanging medium.

5 4. The process of regasifying liquefied gases which consists in filling said gases into a closed thin-walled receptacle disposed within a pressure vessel, and increasing the pressure in said receptacle and between it and the

10 pressure vessel.

5 4. The process of regasifying liquefied gases which consists in filling said gases into a closed thin-walled receptacle disposed within a pressure vessel and adding high pressure

15 gases from an outside source to the receptacle and between it and the pressure vessel thereby to increase the pressure therein.

6. Apparatus for regasifying liquefied gases, comprising a pressure tank, a thin-walled receptacle disposed within and spaced from said tank, the interior of said receptacle communicating with the space between the receptacle and tank, and an auxiliary pressure-gas receptacle in communication with said

25 thin-walled receptacle.

In testimony whereof I have signed my name to this specification.

CHRISTIAN WILHELM PAUL HEYLANDT.
